His Attorney.

UNITED STATES PATENT OFFICE

2,587,665

STEAM IRON WATER RESERVOIR WATER
DISCHARGE CONTROL MEANSAlfred G. Swenson, Ontario, Calif., assignor to
General Electric Company, a corporation of
New York

Application January 7, 1949, Serial No. 69,774

3 Claims. (Cl. 38—77)

1

This invention relates to a pressing device, and it has for its object the provision in a steam iron of improved valve means for controlling the discharge of water from the water reservoir to the steam generating chamber of the iron.

More particularly, this invention relates to improved means for controlling the flow of water from the reservoir to the steam generating chamber of the steam iron described and claimed in the copending application of Frank E. Finlayson, Serial No. 69,756, filed concurrently herewith and assigned to the assignee of the present application, although it is not limited to such iron.

For a more complete understanding of this invention, reference should be had to the accompanying drawing in which Fig. 1 illustrates a side elevation view of an iron embodying the features of my invention, the forward portion of the iron being shown in vertical section, taken along the longitudinal axis of the iron; and Fig. 2 is a fragmentary view of the forward portion of the iron showing the water flow control valve in its open position in contrast to Fig. 1 where it is shown in the closed position.

Referring to the drawing, this invention has been shown as applied to an electrically heated flatiron comprising a sole plate 10, a top cover 11 for the iron, and a handle 12 attached to this cover. A water reservoir 13 is provided within the space defined by the top cover and the sole plate. The handle 12, which preferably is molded from a suitable phenolic condensation product or other heat insulating material, has a hand grip portion 14, a front handle support portion 15, and a rear handle support 16. The rear handle support is provided with a protuberance 16a, and this protuberance in conjunction with the body of the iron forms a heel rest upon which the iron may be up-ended when not in use.

The pressing surface of the iron comprises the sole plate 10 which preferably is cast of a heat-conducting material such as aluminum. Imbedded in the sole plate 10 is a suitable electrical heating element 17 which preferably will be of the sheathed type. While the design of this heating element does not form a part of this invention, briefly the heating element comprises a helical resistance conductor 18 mounted within an outer metallic sheath 19 and supported in spaced relation with reference to the outer sheath by an electrically insulating heat conducting mass 20, such as highly compressed granulated magnesium oxide. The heating element 17 is roughly in the shape of a hairpin with the extremities of its legs extending towards the rear of the iron and its

2

nexus at the forward or pointed end of the iron. Any suitable method may be used for connection of the electrical resistance element 18 to a source of power. A rotatable knob 21, located in a convenient position, is provided for adjustment of a thermostatic switch, not shown, to control the temperature of the iron.

A steam generating chamber 22 is provided adjacent the sole plate so that water from the reservoir 13 dripping into chamber 22 will be vaporized and discharged through the pressing surface of the iron. A cavity 23 is provided in the upper surface of the sole plate 10 into which water from the reservoir may flow. A trough 24 is employed to conduct the water to this cavity 23 so that the water will be spread out over a wider area of the cavity to insure rapid vaporization. Cavity 23 is located between the legs of the heating element 17, and during operation this area of the sole plate will be highly heated and, therefore, the water fed into the steam generating cavity will be instantly flashed into steam. The steam so generated is confined within chamber 22 by a cover plate 25 and hood 27 cooperating with the sole plate 10 to define the walls of chamber 22. Cover plate 25 and hood 27 are fastened to the sole plate by screws 26 or other suitable fastening means. A circuitous passage is preferably provided between the cover plate 25 and the sole plate 10 for conducting the steam from cavity 23 to the steam discharge ports 28. The aforesaid described sole plate structure is described and claimed in the copending application of Frank E. Finlayson, Serial No. 790,525, filed December 9, 1947, now Patent No. 2,582,773, dated January 15, 1952 which is a division of Frank E. Finlayson's copending application, Serial No. 696,298, filed September 11, 1946, now Patent No. 2,557,732 dated June 19, 1951 and both of which are assigned to the assignee of the instant application. Reference also is made to the copending application of Frank E. Finlayson Serial No. 696,297, filed September 11, 1946, now Patent No. 2,499,184, patented February 28, 1950, also assigned to the assignee of the instant application, and which describes and claims a chute extending rearwardly as does trough 24 for conveying water from a reservoir discharge port to a steam generator.

The water reservoir 13 comprises a tank fabricated from a suitable non-rusting material such as brass. This tank 13 may be shaped to fit closely adjacent the underside of the top cover 11 of the iron in order to have sufficient volume 55 of water within the reservoir for continuous use

during the ironing period. The reservoir 13 preferably should be spaced from the sole plate so that water within the reservoir will not be rapidly vaporized. To provide communication between reservoir 13 and chamber 22 and to support the reservoir with respect to the sole plate 10, the valve assembly 29 is securely fastened to reservoir 13 and hood 27 of the steam generating chamber.

Valve assembly 29 includes a bushing 30 internally threaded to receive the orificed member 31. The bushing 30 is fixed to hood 27 by any suitable method and defines an aperture through the top of the hood. Reservoir 13 is provided with an aperture in alignment with the aperture defined by bushing 30, so that when orificed member 31 is inserted through the aperture in the reservoir it may be threaded into bushing 30 to clamp the reservoir and hood together. A suitable gasket 33 may be interposed between the bushing 30 and the underside of the reservoir to provide a sealed connection between the reservoir 13 and the hood 27. The orifice 34 passing through the member 31 permits flow of water from the reservoir into the steam generating chamber. The diameter of this orifice should be such as will allow the water to drip into the steam chamber during a normal pressing operation. Other means will, of course, be apparent to one skilled in the art for supporting the reservoir and furnishing communication between the reservoir and the steam generating chamber.

A fill tube or riser 35 furnishes communication to the reservoir for addition of liquid. An opening is provided into the water tank 13 at its upper forward portion for reception of this fill tube, and a similar aligned opening is also provided in the top cover 11 of the iron. Fill tube 35 extends through these aligned openings and is connected to both the top cover and the reservoir by any suitable method well known to the art. As shown in the figure, an annular groove 36 is provided on the lower end of fill tube 35, and this groove receives the edge portions of the aperture in the reservoir. An insulating gasket 37 and a washer 38 around the outside of the tube 35 may be employed between the top cover 11 of the iron and the front handle support 15. Such a construction will aid in preventing the handle from becoming uncomfortably hot during operation.

The front handle support 15 has an internal bore of an appropriate shape to receive snugly the fill tube 35. The strength of this portion of the handle may be increased by employing a liner 39, and this liner, as shown in the drawing, is a cylindrical tube closed at its upper end. The liner 39, fill tube 35, and the handle 12 are connected together by means of the screw 40, and this assembly also serves as a means for attaching the front handle support 15 to the body of the iron.

A filling, venting and emptying aperture 41 is provided for the reservoir 13. This aperture is defined by the aligned openings provided through the front handle support 15, liner 39, and fill tube 35. It will be noted that this filling opening 41 faces the front or pointed end of the iron so that when the iron is on its heel rest, the aperture faces upwardly to permit water to be poured from a small pitcher, or the like, into the fill tube for adding water to the reservoir. This construction has the distinct advantage over the conventional arrangement where water is added to the reservoir while the iron is in its normal ironing position, in that with this

construction any overflow while filling the water tank will merely flow over the handle portion of the iron and will not strike the hot surfaces of the iron. This arrangement also facilitates the filling of the reservoir in that the iron is on its heel rest during this time and there is no danger of burning or scorching the material being ironed or the surface of the ironing board. It is contemplated in this construction to employ no means whatsoever for closing the filling aperture 41, and therefore no special means need be provided for venting the water reservoir. Aperture 41 also provides a means by which the water from the reservoir may be poured out upon completion of ironing.

The foregoing structure is substantially the same as the Figs. 1 and 2 form of the invention described and claimed in the copending application of Frank E. Finlayson, Serial No. 69,756, filed concurrently herewith.

In accordance with my invention, control means are provided for opening the reservoir so that water may flow to the generative chamber 23, or for shutting this flow of water off. And this means includes means whereby these functions may be accomplished easily while ironing by a simple movement of the thumb or thumb and forefinger. Such steam control member also is of the utmost simplicity to reduce the cost of manufacture, to increase the ease of operation, and to provide a device of high reliability without the need for painstaking maintenance or expensive repairs.

In accordance with my invention, the control means comprises a control member 43 formed from a resilient piece of wire of approximately the same diameter as the diameter of the orifice 34. Member 43 includes a lower straight portion 44 which projects through the orifice for blocking off the flow of water to the steam generating chamber. An intermediate bowed portion is formed on member 43 to frictionally engage the inside wall of fill tube 35, and a finger control loop 45 is formed on the upper end of flow control member 43. By such a construction, this valve operating member 43 is slidable vertically by the operator to permit the flow of water from the reservoir to the steam generating cavity, and the valve is held in the open, closed, or an intermediate position by the frictional engagement of the intermediate bowed portion with the inside wall of the fill tube. Member 43 is of sufficient length to allow the lower plug portion to extend through the orifice so that when the flow control member is forced downwardly to close off orifice 34, any scale or dirt within the orifice will be forced out.

While I have shown a particular embodiment of my invention, it will be understood, of course, that I do not wish to be limited solely thereto since modifications may be made, and I, therefore, contemplate by the appended claims to cover any such modifications as fall within the true spirit and scope of my invention.

What I claim as new and desire to secure by Letters Patent of the United States is:

1. A steam iron comprising a water tank, a flash steam generator located adjacent thereto, means furnishing communication between said tank and said steam generator, means for heating said generator for flashing the water fed into it from said tank into steam, a fill tube having one of its ends fixed to said reservoir and extending upwardly when said iron is in normal ironing position, and a water feed control mem-

ber extending longitudinally through and frictionally engaging the inside wall of said fill tube, said control member being slidably movable longitudinally of said fill tube and having a plug portion adapted to seal off said communicating means, and a finger operated control member positioned outside the other end of said fill tube for manually adjusting the rate of water flow.

2. A steam iron comprising a water reservoir, a steam generating chamber, a valve furnishing communication between said reservoir and chamber, means for heating said chamber to generate steam from the water fed into it from said reservoir, a fill tube connected to and extending away from said reservoir with one of its ends affixed thereto, a handle for said iron provided with a hollow bore adapted to receive said fill tube, a control member for said valve extending longitudinally through and frictionally engaging the inside wall of said fill tube, said control member being slidably movable longitudinally of said fill tube, and a finger operating portion on said control member projecting outside the opposite end of said fill tube and handle.

3. A steam iron comprising a water reservoir, a steam generating chamber, an orificed member providing a water flow passage from said reser-

voir to said chamber, means for heating said chamber to generate steam from the water fed into it from said reservoir, a fill tube having one of its ends affixed to said reservoir and extending upwardly when said iron is in normal ironing position, and a water feed control member extending longitudinally through said tube, said feed control member including a plug portion adapted to seal off said orifice, a finger operated control member positioned outside the other end of said fill tube, and an intermediate bowed portion providing frictional engagement of said feed control member with the inside surface of said tube, said feed control member being slidably longitudinally within said tube to regulate water flow through said orificed member.

ALFRED G. SWENSON.
